W. H. Campfield,
ATTORNEY.

UNITED STATES PATENT OFFICE.

ANDREW O. BURGESS, OF NEWARK, NEW JERSEY, ASSIGNOR TO A. L. NEWMAN COMPANY, OF PROVIDENCE, RHODE ISLAND.

METHOD FOR MAKING COMPOSITE RINGS.

1,415,520.

Specification of Letters Patent. Patented May 9, 1922.

Application filed October 1, 1920. Serial No. 414,009.

To all whom it may concern:

Be it known that I, ANDREW O. BURGESS, a citizen of the United States, and a resident of Newark, county of Essex, and State of New Jersey, have invented certain new and useful Improvements in Methods for Making Composite Rings, of which the following is a specification.

This invention relates to an improved method for making composite rings, and while it is applicable to many different articles and metals and alloys of metals, in order to make the description clear and its advantages apparent I will particularly describe 10 its application to the manufacture of finger rings.

By my improved method it is possible to make a ring with a core or base of a precious metal or semi-precious or base metal, and 20 provide it with a covering of precious metal, the finished product having no seams or soldered portions.

The invention is illustrated in a manner to make clear the successive steps, and in the 25 accompanying drawing Figure 1 is a plan and Figure 2 an edge view of a blank of sheet metal. Figure 3 shows the blank formed into a cup-shaped article. Figures 4 and 5 are a plan and side view, respectively, 30 of a ring used as a core or base of the finished article. Figure 6 is a section showing the cup and the ring assembled. Figure 7 is a similar view showing the same elements with the edge of the cup crimped over the 35 ring. Figure 8 is a section to illustrate what parts of the structure of Figure 7 are removed, and Figure 9 is a side view of the finished article.

I provide, first, a sheet of metal, and for 40 the purpose of illustration I will mention platinum, which sheet 10 is shown in Figures 1 and 2. I form this sheet into a substantially cup-shaped article shown in section in Figure 3. This cup 11 is preferably made 45 with its bottom inset, as at 12, to provide an annular seat 13 between the bottom 12 and the marginal flange or side wall 14.

I provide also a ring or core 15, which may 50 be hollow or solid, usually solid, and is of metal that melts at a lower temperature than the sheet 10. For the purpose of description I will define the ring 15 as of gold.

The ring 15 is placed in the cup-shaped article, as in Figure 6, the parts being pro-

portioned so as to provide a snug fit. The 55 side walls 14 are then folded over or crimped, as at 16, so that the ring is encased and the joint 17 is on the inner face of the ring. When it is desired to insure a positive joining of the parts, the article shown in Figure 60 7 is subjected to a temperature too low to affect the sheet of material encasing the ring, but high enough to cause the ring itself to fuse with the casing. In the form described the temperature would be sufficient to cause 65 the gold to fuse with the inner face of the platinum sheet, but the platinum would be unaffected.

The article is then operated on to remove the center part, including the inner edge of 70 the folded sheet and of the ring. This is clearly shown in Figure 8, where, in the lower part of the figure, is illustrated at a the portion removed, but not showing exactly its shape on removal, and in the upper part, 75 as at b, is illustrated the finished article.

It will be seen that the ring as shown in Figures 8 and 9 is seamless, that is, there are no soldered or welded joints around its periphery, and the ring has the appearance of 80 a platinum ring, but its cost is less, as the core is of gold. This method of ring making is applicable to articles other than finger rings, and I do not wish to be understood as 85 limiting myself to these articles.

What I term the finished article is finished 90 so far as my method is concerned and is usually ornamented and embellished on its surface before it is ready for sale.

I claim:

1. A method of making a composite ring comprising the provision of a ring of metal, the provision of a sheet of metal, folding the sheet around the ring so that the edges of the sheet are at the inner face of the ring, 95 and then cutting away the inner edge of the ring and of the folded sheet.

2. A method of making a composite ring comprising the provision of a ring of metal, the provision of a sheet of metal, folding the sheet around the ring so that the edges of the sheet are at the inner face of the ring, subjecting the parts thus assembled to a temperature to cause the ring to be fused to the sheet, and then cutting away the inner edge 100 of the ring and of the folded sheet.

3. A method of making a composite ring comprising the provision of a sheet metal

blank, the provision of a ring made of metal that melts at a lower temperature than the sheet, forming the sheet into a cup, placing the ring in the cup, crimping the edges of the cup around the ring, subjecting the assembled parts to a temperature to cause the ring to fuse to the inside face of the sheet

metal, and then removing the inner edge of the crimped sheet and of the ring.

In testimony that I claim the foregoing, I have hereto set my hand, this 28th day of September, 1920.

ANDREW O. BURGESS.
